UNITED STATES PATENT OFFICE.

PATRICK McMANAMAN AND JULIUS NAMET, OF CLEVELAND, OHIO.

DESIGN FOR A COMBINED SIGNAL CASING AND TAG HOLDER.

Application filed December 10, 1926. Serial No. 20,019. Term of patent 14 years.

To all whom it may concern:

Be it known that we, **PATRICK McMANAMAN**, a citizen of the United States, residing at Cleveland, county of Cuyahoga, and State of Ohio, and **JULIUS NAMET**, a subject of Hungary, residing at Cleveland, county of Cuyahoga, and State of Ohio, have invented a new, original, and ornamental Design for Combined Signal Casing and Tag Holder, of which the following is a specification, reference being had to the

accompanying drawing, forming part thereof.

Figure 1 is a front view, and Figure 2 is a side view of a combined signal casing and tag holder, showing our new design.

We claim:

The ornamental design for a combined signal casing and tag holder, as shown.

**PATRICK McMANAMAN.
JULIUS NAMET.**
